Des. 182,025
Patented Feb. 4, 1958

182,025

WINDOW VENTILATOR

Pauline Groleau, née Gagnon, Three Rivers, Quebec,
Canada

Application February 5, 1957, Serial No. 44,760

Term of patent 14 years

(Cl. D62—4)

Fig. 2

Fig. 3

Figure 1 is a perspective view of a window ventilator showing my new design; Figure 2 is a transverse cross-section on the line 2—2 of Figure 1; and Figure 3 is an end elevation thereof.

I claim:

The ornamental design for a window ventilator, as shown.
